UNITED STATES PATENT OFFICE.

JOHN F. A. HOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,282, dated May 7, 1895.

Application filed April 4, 1895. Serial No. 544,498. Term of patent 3½ years.

To all whom it may concern:

Be it known that I, JOHN F. A. HOORT, a citizen of the United States, residing at New York, in the county of New York and State of New York, have invented and produced a new and original Design for a Mantel; and I do hereby declare the following to be a full, clear, and exact description of the same, reference being had to the accompanying drawing, forming a part thereof.

The figure of the accompanying drawing is an isometric view of the new design for mantels. Its leading feature consists in the design for a mantel comprising the rectangular paneled columns two on each side extending nearly the whole height of the article and supporting the mantel shelf and a cornice.

Numerals 1 denotes the mantel shelf and 2 a cornice. The former has supporting columns 3 of rectangular form in cross section

and are provided with sunken panels 4. The upper columns 3 have similar panels. The lower columns are ornamented by a frieze having an oval ornament and the upper columns are surrounded by a part having foliations 7.

The central part 5 of the mantel shelf extends forward of the main part thereof and the extension has beneath it a supporting panel 6.

What I claim is—

The design for a mantel shown and described.

In testimony whereof I affix my signature in presence of two witnesses.

JOHN F. A. HOORT.
